TROMBONE

Davis Shuman, Brooklyn, N. Y.

Application February 17, 1950, Serial No. 144,740

3 Claims. (Cl. 84—395)

1

The present invention relates to wind instruments and more particularly to slide trombones.

Heretofore slide trombones have been made with the bell, mouthpiece and slide almost parallel with the result that the trombonist requires a substantial amount of room in front of him. Very often, the space allotted to an orchestra or band is insufficient to provide so much room and it is necessary for the trombonist to point the bell downwards so that the bell does not directly face the audience or dance floor. For this reason the effect of the trombone is diminished or even lost. In addition, when the slide of the straight slide trombone is fully extended, the instrument becomes unbalanced and it is difficult for the trombonist to hold the instrument in proper balance.

I have found that these difficulties can be avoided by inclining the telescopic sections and the slide of the trombone at an angle to the axis of the bell and mouthpiece so that the slide can be moved at an angle to avoid striking a person in front of the trombonist without the necessity of directing the bell away from the audience. Inclining the slide also improves the balance of the instrument since, in normal playing position, the horizontal extension of the slide is not as great as in the conventional trombone and the arm movement is easier and more natural.

One of the objects of the present invention is to provide a trombone which can be conveniently played in a relatively small space.

Another object of the invention is to provide a trombone in which the slide is inclined at an angle to the bell.

A further object is to provide a new and improved water pail for wind instruments.

These and other objects and advantages reside in certain novel features of construction, arrangement and combination of parts as will hereinafter be more fully set forth and pointed out in the appended claims.

Referring to the drawing:

Figure 1 is a perspective view of a trombone embodying my invention.

Figure 2 is an enlarged fragmentary elevation of my trombone showing the relationship of the mouthpiece, bell branch and slide.

Figure 3 is a section taken on line 3—3 of Figure 1.

Figure 4 is an enlarged detail elevation of my improved water pail with parts broken away to show internal structure.

Figure 5 is a section taken on line 5—5 of Figure 4.

2

In the drawing, my invention is illustrated in connection with a trombone having the usual bell 10, bell section 11, bell bow 12 and bell branch section 13. The usual bell braces 14, 15, and 16 connect the bell section 11 and bell branch section 13. The usual mouthpiece 17 is rigidly connected to the bell branch section 13 by a brace 18. As clearly shown in Figure 1, the axes of the bell 10 and mouthpiece 17 which, it is to be understood, are normal to the plane of their respective openings, are substantially parallel so that the trombonist faces in the same direction as the bell.

Telescopic extensions 20 and 21 (Figure 3) project from the bell branch section 13 and mouthpiece 17 respectively. In my new trombone, the telescopic sections 20 and 21 are parallel to each other but are connected to the bell branch section 13 and mouthpiece section 17 by elbows 13a and 17a respectively and are inclined at an angle to the axis of the bell 10. A slide indicated generally at 22 has two parallel arms 23 and 24 slidably mounted on the telescopic sections 20 and 21 respectively. The angle of the telescopic sections 20 and 21 is not critical but I prefer to incline them at an angle of about 45 degrees to the axis of the bell 10 since at this angle and with the instrument in normal playing position, the vertical and horizontal projections are a minimum for a particular position of the slide 22.

The arms 23 and 24 are connected and the slide 22 is operated by a slide brace 25 and, to facilitate the playing of the instrument, a sleeve 26 is rotatably mounted on the slide brace 25 preferably on ball bearings indicated at 27. In playing the instrument the trombonist may grip the sleeve 26 throughout the full range of movement of the slide 22 and thus maintain continuous and firm control of the slide.

The slide 22 is provided with a water key indicated generally at 30. The water key 30 consists of a lever 31 pivotally connected to the slide 22 as indicated at 32. One end of the lever 31 is provided with a plug or stop 33 which closes an opening 34 in the wall of the slide 22. A spring 35 engages the lever 31 to urge the plug or stop 33 to close the opening 34. In any trombone or other wind instrument, water collects as the instrument is played and this water may be eliminated from the trombone by depressing the free end of the water key which raises the stop or plug 33 from the opening 34 and permits the water to run out. Ordinarily this water is permitted to run onto the floor but the water pail

shown in Figures 4 and 5 eliminates the need for this offensive and messy practice.

My water pail consists of a cylindrical cup 40 which may be of metal, plastic or other suitable material. One end of the cup is open and the side wall adjacent the open end is provided with a notch 41 which is wide enough to pass over the water key lever 31. The open end of the cup 40 is placed over the end of the water key at the opening 34 and may be secured in position by any suitable means such as a wire 42 extending around the slide 22. The cup 40 is filled with absorbent material 43 such as cotton. When this water pail is used, the water is absorbed by the material 43 when the water key is actuated and even the absorbent material contained in a small cup about the size of a thimble, will be sufficient to take up the water resulting from playing several numbers. When the material 43 becomes soaked it can be readily replaced.

My new trombone presents many advantages over the conventional instrument. Because the slide does not come directly toward the mouth, there is less danger of injury to the mouth, lips or teeth while playing in a standing, sitting or marching performance. The operation of the slide is more natural and the fifth, sixth and seventh positions may be easily reached without awkwardness. The reduced overall reach required permits boys to learn to play on a standard instrument and the more natural direction of movement permits more rapid slide operation and greater technique thus enhancing the scope of the trombone as a solo instrument.

The angular slide improves the balance of the instrument even when the slide is at its extended position thus reducing the physical strain on the trombonist and the sleeve on the slide brace aids in eliminating distortion during play. Because the slide is inclined downwardly, the bell will still face the audience and the sound will not become diminished as in the conventional trombone. With my improved water pail, the instrument will be such as to satisfy the most fastidious.

Conventional trombones may be converted to my new construction by applying elbows 13a and 17a and connecting the bell branch section 13 and mouthpiece 17 to the telescopic sections 20 and 21. However, the bell 11 may have to be shortened to keep the instrument at the same pitch as originally tuned.

The invention may be embodied in other spe-

cific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patent is:

1. A slide trombone comprising a bell section including a bell on one end thereof, a bell branch section substantially parallel to said bell section, a bell bow connecting the end of said bell section remote from said bell to one end of said bell branch section, a first telescopic section connected to the opposite end of said bell branch section, a second telescopic section secured to said first telescopic section in parallel relation thereto, and a playing slide for the selection of a normal playing range of tones freely slidably mounted on said telescopic sections, the longitudinal axis of said first telescopic section being angulated with respect to said bell branch section in a direction away from the axis of said bell section so as to form an obtuse included angle of substantially less than 180° between the connected ends of said bell branch section and first telescopic section.
2. The slide trombone defined in claim 1 wherein said included angle lies substantially in the plane defined by the longitudinal axes of said bell section and said bell branch section.
3. The slide trombone defined in claim 2 including a mouthpiece mounted on said second telescopic section, the axes of said mouthpiece and said second telescopic section being relatively angulated to define an angle substantially the same as said obtuse included angle.

DAVIS SHUMAN.
